UNITED STATES PATENT OFFICE.

CHARLES HERBERT OCUMPAUGH, OF ROCHESTER, NEW YORK.

DESIGN FOR A PULLEY-FRAME.

SPECIFICATION forming part of Design No. 28,397, dated March 22, 1898.

Application filed January 25, 1898. Serial No. 667,936. Term of patent 14 years.

To all whom it may concern:

Be it known that I, CHARLES HERBERT OCUMPAUGH, a citizen of the United States, residing at Rochester, in the county of Monroe and State of New York, have invented and produced a new and original Design for a Pulley-Frame; and I do hereby declare the following to be a full, clear, and exact description of the same, reference being had to the accompanying drawings, forming a part thereof.

Figure 1 is a perspective of a pulley-frame, showing my new design. Fig. 2 is a front elevation. Fig. 3 is a section on line xx of Fig. 4. Fig. 4 is a section on line yy of Fig. 2.

As shown in the drawings, the leading or material feature of my design consists of the rounded portions 1, intermediate the ends 2

of the face-plate 3. The curve of each portion 1, rounded transversely to the face-plate, disappears in a side plate 4 in one direction and in the face-plate in the opposite direction. The rounded portion lengthwise of the same is coterminous with the adjacent side plate.

5 denotes shoulders situated at the ends of the parts 1, and said shoulders terminate the outline of the ends 5 of the face-plate.

Having described my invention, what I claim as new, and desire to secure by Letters Patent, is—

The design for a pulley-frame, as herein shown and described.

CHARLES HERBERT OCUMPAUGH.
